US00D625846S

(12) **United States Design Patent**
Scott

(10) **Patent No.:** US D625,846 S
(45) **Date of Patent:** ** Oct. 19, 2010

(54) **LAYOUT FORM FOR EMBEDDING OBJECTS
IN A SETTABLE MATERIAL**

6,186,469 B1 2/2001 Scott

* cited by examiner

(75) Inventor: **Samuel C. Scott**, Denver, CO (US)

Primary Examiner—Doris Clark

(73) Assignee: **Scott System, Inc.**, Denver, CO (US)

(74) Attorney, Agent, or Firm—Dorr, Carson & Birney, P.C.

(**) Term: **14 Years**

(57) **CLAIM**

(21) Appl. No.: **29/322,329**

The ornamental design for a layout form for embedding objects in a settable material, as shown and described.

(22) Filed: **Aug. 1, 2008**

DESCRIPTION

(51) **LOC (9) Cl.** **25-01**

FIG. 1 is a perspective view of a layout form for embedding objects in a settable material showing my new design.

(52) **U.S. Cl.** **D25/199**

FIG. 2 is a top plan view thereof.

(58) **Field of Classification Search** 249/13,

FIG. 3 is a bottom plan view thereof.

249/16, 61; 52/749.11, 384; D25/199

FIG. 4 is a front elevational view thereof.

See application file for complete search history.

FIG. 5 is a detail front elevational view of a portion of the layout form for embedding objects in a settable material in FIG. 4.

(56) **References Cited**

FIG. 6 is a rear elevational view thereof.

U.S. PATENT DOCUMENTS

FIG. 7 is a detail rear elevational view of a portion of the layout form for embedding objects in a settable material in FIG. 6.
